(57) **CLAIM**

The ornamental design for a thermostat with removable trim plate, as shown and described.

DESCRIPTION

FIG. 1 is a top-front-right isometric view of a thermostat with removable trim plate showing our new design;

FIG. 2 a top-right-rear isometric view thereof;

FIG. 3 is front view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof.

The broken lines are for the purpose of illustrating portions of the thermostat with removable trim plate that form no part of the claimed design.
